UNITED STATES PATENT OFFICE.

HARVEY H. ASKEW, OF LOS ANGELES, CALIFORNIA.

RAILWAY-CROSSING.

1,312,090.

Specification of Letters Patent.

Patented Aug. 5, 1919.

Application filed November 27, 1915. Serial No. 63,755.

To all whom it may concern:

Be it known that I, HARVEY H. ASKEW, a citizen of the United States, residing at Los Angeles, in the county of Los Angeles and State of California, have invented certain new and useful Improvements in Railway Crossings, of which the following is a specification.

This invention relates to improvements in a railway crossing and especially such as must be used where tracks, crossing each other are ordinarily formed with considerable gaps or openings for the passage of the wheel flanges on the rolling stock of the road.

It is an object of the invention among other things, to provide a crossing in which a substantially continuous and unbroken support will be offered the wheels of rolling stock, no matter in which direction the travel may be.

It is also an object of the invention to provide adjustable wheel supporting elements for bridging the spaces between the main portions of the track at a railway crossing, means also being provided for the depression of said intermediate members when necessary to accommodate the flange of passing railway wheels.

It is a further object of the invention to provide a railway crossing with depressible members adapted to form continuous wheel supports between the parts of the crossing and to provide supporting means capable of being thrown beneath said depressible members for holding them in wheel supporting position.

It is a still further object of the invention to provide a railway crossing with depressible members for completing wheel supporting portions of the tracks at a crossing and to provide spring actuating supports, normally holding the said depressible members in wheel supporting position, means being also provided for automatically throwing the supporting means out of supporting position so that the depressible members may yield under the action of the wheel flanges.

With these and other objects in view, the invention comprises certain novel constructions, combinations and arrangements of

parts as will be hereinafter more fully described and claimed.

In the accompanying drawing forming a part of this specification:

Figure 1 is a top plan view of a railway crossing embodying the features of the present invention.

Fig. 2 is a longitudinal central sectional view through one of the track portions of a crossing, and showing the mechanism for operating the track supporting means at the crossing.

Fig. 3 is a detail sectional view of the portion of the switch mechanism showing a modified form of means for throwing the supports out of supporting position.

Fig. 4 is a top plan view of a modified form of a railway crossing, in which the supports for the depressible sections are normally out of supporting position.

Fig. 5 is a vertical sectional view taken upon the line *a*—*b* of Fig. 4.

Fig. 6 is a fragmentary detail sectional view taken through one-half of the crossing and showing one of the cradles depressed by the passage of car wheels.

Fig. 7 is a perspective view of one of the cradles shown in full lines and a companion cradle shown in dotted lines together with some of the details of the crossing also shown in position.

In the accompanying drawing preferred embodiments of the invention have been shown and the details and features thereof will now be more specifically described with reference thereto. In the accompanying drawing 5 and 6 indicate fixed rails of a crossing, the said rails being shown at right angles to each other, though of course, it will be readily understood that they may be arranged at various angles with respect to each other without departing in the least from the spirit of the invention. The said crossing is also provided with intermediate wheel supporting members 7 and 8 adapted to bridge the space between the fixed portions 5 and 6 of the crossing. The wheel supporting portions 7 and 8 are depressible devices which may be termed cradles and have side bars 9 and 10 respectively and wheel engaging end portions 11 and 12. These side bars 9 and 10 and the

end portion 11 and 12 extend parallel with the fixed rails 5 and 6, there being sufficient space left between the parts to permit of their free movement up and down, as is clearly shown in Fig. 1 of the drawing. The wheel supporting portions 7 and 8 of each cradle extend transversely thereof in alignment with the fixed rails 5 and 6, so as to form extensions thereof and fill the space 10 between the fixed sections 5 and 6 at the crossing.

The wheel supporting portions 7 and 8 of the impending cradles are adapted to be positively held in wheel supporting position 15 by removable supporting members 13 and 14, there being oppositely arranged members 13 for supporting the member 8 and oppositely arranged members 14 for supporting the members 7. These supporting members 20 are preferably hinged at 15 upon the base 16 of the crossing mechanism and their lower edges usually rest in sockets 17, so that the weight placed upon them comes substantially upon the base 16 of the said 25 crossing mechanism. The supporting members 13 and 14 are preferably provided with flanges 18 which limit their inward movement, when they are moved into vertical position beneath the wheel supporting members 30 7 and 8. The said members 13 and 14 are normally held in upright track supporting position by springs 19 interposed between them and fixed brackets 20.

Oppositely arranged supporting members, 35 as for instance the members 13, are arranged to have opposite simultaneous movement, each of said members being connected by links 21 with the opposite ends of a cross lever 22 which is centrally pivoted upon a standard 23 supported on the base 16 of the mechanism. By means of this structure, when one member 13 is moved outwardly, the opposite member 13 will be moved outwardly also or both moved inwardly as the 45 direction of movement may be. The other supporting members 14 are likewise connected together, and are moved by rods pivoted to a cross member or bar 24 also pivoted upon the upper end of the standard 23.

With the wheel supporting portions of the track normally held in their uppermost positions by the supporting members 13 and 14, means must be provided for removing the said supports 13 and 14 from beneath the track sections when the flanges of the car 50 must pass the crossing. This may be accomplished automatically or positively by hand or any other actuating mechanism. The device shown in Figs. 1 and 2 whereby the parts may be removed automatically embraces pivoted trip bars 25, usually pivoted in the groove 26 of the rail. The inner ends of said trip members 25 are connected by rods 27 with an arm 28 carried by a trans-

verse shaft 29 and secured thereto. The 65 said shaft will be rocked by the trip pieces 25. Arms 30 also project from the shaft 29 and have a pin and slot connection 30^a with thrust bars 31. The said thrust bars 31 are pivotally connected at their inner ends as 70 at 32 to the rocking supporting members 13. When a car approaches the crossing the flanges of its wheels will depress the trip members 25 causing a rocking of the shaft 29 and the pulling of the adjacent supporting member 13 from beneath the rail section supported by it, as is clearly shown in Fig. 3 of the drawing. The interconnecting links 21 and cross lever 22 between said member 13 and the one opposite thereto will 75 simultaneously cause the other supporting member 13 to be moved from beneath the track, normally resting upon it. The slotted connection 30^a between the arms 30 and the thrust bars 31 permit the movement of the 80 said supporting sections 31 without affecting the other mechanism, as will be readily understood. The same mechanism is provided for the movement of the supporting sections 14 when a car approaches the crossing upon 85 the other track. The joints 13^a and 14^a between the supporting sections 13 and 14 and the wheel supporting track sections or members 7 and 8 normally resting thereon is protected from falling of dirt, foreign substances and the like between the parts by an inclined projecting flange 33 which is secured to the outer surface of each supported track section as clearly shown in Fig. 2 of the drawing.

The cradles carrying the supporting track sections are normally held in their uppermost positions by springs 40 which are mounted upon brackets 41 arranged beneath the end portions of said cradles. The upward movement of the said cradles under the action of the springs 40 is limited in any desired manner as for instance by projections 42 formed upon the ends of the cradles and extending underneath the ends of the 110 adjacent rails 26 as clearly shown in Fig. 2. Of course, other arrangements of the springs and of limiting means may be employed without departing in the least from the spirit of the invention.

The parts for supporting the track sections may also be manually operated when it is desired to hold the parts in a given position when a car or train is to pass one way over the crossing. Thus the cross lever 22 115 may be provided with an actuating arm 34 connected by means of a rod 35 with a lever 36 arranged outside the crossing. The operation of the lever 36 may be made to positively throw the supporting sections 13 out of track supporting position or back into position again when desired. The other cross bar or arm 24 is also provided with an

actuating arm 37 connected by a rod 38 with a lever 39 which is similar to lever 36, whereby the members 14 may be manipulated manually when desired. The said levers 5 may be provided with the usual notched segments and with a spring actuated pawl or bolt for holding the lever in its adjusted position, as for instance as shown in Fig. 3.

In the modified form shown in Fig. 4, for 10 instance, the depressible interlocking track sections may be free to descend under the action of the wheel flanges, the supporting members in this instance being normally out of supporting position instead of in supporting 15 position as in the form of device shown in Fig. 1. With this form of the device also the depressing of one of the cradles upon the approach of rolling stock, operates immediately to move the supporting devices 20 beneath the other cradle, so as to hold the track sections firmly in elevated position beneath the treads of the wheels. Thus the crossing of this modified form may be provided with wheel supporting sections 44 and 25 45 forming parts of cradles 46 and 47 and being fitted within the crossing tracks 48 and 49. Immediately beneath the wheel supporting sections 44 and 45 are rocking supporting 30 members 50 and 51 which are pivoted or otherwise movably supported upon the base of the crossing so that they may be brought vertically beneath the said wheel supporting sections 44 or 45. The upper edges of the said supporting members are 35 provided with flanges 52 for limiting the inward movement of the said supporting members. Springs 53 connect the upper edges of said supporting members with standards 54 which rise from the base of the crossing, 40 the said springs normally keeping the supporting members in their open or outwardly rocked positions as shown in Fig. 5 of the drawing. The structure of the device is also such that when one of the cradles is depressed by the flanges of car wheels, the 45 rocking supporting members of the other cradle will be thrown beneath the wheel supporting sections to be used by the car. For this purpose hinged trip pieces 55 are mounted at the lower edge of each supporting 50 member and are provided with inwardly projecting, cradle engaging lips 56. The outer ends of the trip members 55 extend upwardly outside the supporting members 50 and 51 and springs 57 are interposed between the two members, the structure being 55 such that when the cradle is depressed upon the lips 56 the outer end of the trip pieces 55 will be forced against the springs 57 sufficiently to carry the supporting members 50 and 51 into vertical position beneath the wheel supporting track sections. The structure is thus such that when the car wheels strike the cradle 47 and depress it, the sup-

porting members 50 will be thrown inwardly 65 immediately and beneath the track sections 45 so as to support the track sections 45 in elevated position in alinement with the rails 49. A continuous wheel supporting surface is thus provided for each wheel in passing 70 the crossing. When a car approaches upon the tracks 48, the wheels will depress the cradle 46 and throw the supporting members 51 under the wheel supporting sections 44. Flanges 58 are preferably provided on 75 the outer sides of the wheel supporting track sections 44 and 45 so as to cover the joint between the supporting members and the said track sections, against the falling of dirt or grit into the working parts of the 80 mechanism and interfering with its operation.

The perspective view illustrated by Fig. 7 shows the interlocking cradles with notches or openings 68 provided, which allows one 85 cradle to impend the other and permit ample space for the up and down movement of the parts when wheels are passing over the crossing. The interlocking cradles are disposed parallel to the crossing tracks and 90 when in operative position form a continuous and noiseless crossing.

The construction of the railway crossing may be modified in various ways, the supporting members 13 may be constructed to 95 swing from the inside instead of from the outside as shown, and it will thus be evident that many of the minor details of construction may be changed in embodying the invention in practical form and many mechanical equivalents may be substituted for the parts described and shown all within the 100 spirit and scope of this invention.

What is claimed is:

1. A railway crossing having transverse 105 sections adapted to bridge the space between the adjacent ends of crossing road ways, movable members adapted to be rocked back and forth beneath said transverse sections, movable means adapted to move said rocking members whereby flanges of wheels may operate the said members in one direction, and springs normally moving said rocking members in the opposite direction.

2. A railway crossing having depressible 115 track sections, supporting members adapted to be moved beneath said track sections when they are to be made to support wheels, trip members carried by said movable supports and adapted to be operated by the depression of one set of track sections and spring means for withdrawing the said supports from beneath the said track sections when the wheels are passing the crossing.

3. A railway crossing having depressible 125 track sections, rocking supports beneath said sections and adapted to be brought in alinement therewith for holding them in wheel

supporting position, springs normally holding said supports out of wheel supporting position, pivoted trip members carried by said supports and adapted to be operated by 5 one set of track sections, whereby the other set of track sections at the crossing will be supported by the supporting members beneath them and flanges overhanging said supporting sections and movable parts there-

of for protecting them against dirt or other 10 foreign materials.

In testimony whereof I have hereunto set my hand in presence of two witnesses.

HARVEY H. ASKEW.
